UNITED STATES PATENT OFFICE.

WILLIAM BENNIE, OF BROWNWOOD, TEXAS.

COTTON-PICKER.

SPECIFICATION forming part of Letters Patent No. 760,413, dated May 24, 1904.

Application filed February 10, 1904. Serial No. 193,029. (No model.)

To all whom it may concern:

Be it known that I, WILLIAM BENNIE, a citizen of the United States, residing at Brownwood, in the county of Brown and State of Texas, have invented certain new and useful Improvements in Cotton-Pickers; and I do declare the following to be a full, clear, and exact description of the invention, such as will enable others skilled in the art to which it applies to make and use the same, reference being had to the accompanying drawings, and to the letters of reference marked thereon, which form a part of this specification.

This invention relates to new and useful improvements in pneumatic apparatus for conveying cotton when picked from the plant, and comprises a suction-fan and casing therefor, which latter has pipes through which air is drawn and which are carried by a cotton-picker and attached to his or her wrist convenient to the hands of a picker, whereby as a boll of cotton is detached from the bur of a plant it may be drawn into the pipe and conveyed to a wagon or other receptacle carrying the fan.

My invention consists, further, in various details of construction and in combinations and arrangements of parts, which will be hereinafter fully described and then specifically defined in the appended claim.

I illustrate my invention in the accompanying drawings, in which—

Figure 1 is a perspective view showing the application of my device. Fig. 2 is a side view 35 of the casing in which the suction-fan is mounted. Fig. 3 is a sectional view through the motor-casing and fan lengthwise of the axis of the fan. Fig. 4 is a top plan view of the casing. Fig. 5 is a detail view of one of the 40 suction-pipes. Fig. 6 is a cross-sectional view through the fan and box.

Reference now being had to the details of the drawings by letter, A designates a motor-casing having a fixed platform A', and C designates a shaft journaled in said casing, and 45 fixed to said shaft is a pulley B, (shown in Figs.

2 and 3 of the drawings,) whereby power may be imparted to a shaft C. One or more fans D are fixed to the shaft inside the casing, and screens C' are interposed between the outer 50 portions of the fans and the end walls of the casing, whereby the cotton is prevented from coming in contact with said fans. Projecting from the opposite ends of the casing is a branching pipe E, having the pipes E', to 55 which flexible tubing or hose-pipe F is connected, as shown in Fig. 1 of the drawings. The outer end of each tubing has a flaring portion H and two eyes K, through which the straps K' may be passed to hold the ends of 60 the hose-pipes against the wrists of the operator, with the flaring end of each pipe near the hand of the operator in such a position as to immediately be clapped over the end of the pipe when not in use. 65

N N in Figs. 2 and 3 designae exit-apertures through which the cotton-bolls which have been sucked through by the motor may be expelled into a receptacle of any suitable kind. 70

The operation of my apparatus is as follows: A motor is adapted to be carried by a conveyance to which the fan-casing is secured, whereby a rotary movement may be imparted to the fan for the purpose of creating a suction. The 75 operator or operators attach the tubes to their wrists and walk along the rows of cotton, and after a boll of cotton is plucked from the cup or bur in which it grows it is inserted by the operator in the flaring end of the hose-pipe 80 and suction immediately carries the same to the motor-casing, from which it is expelled through the exit-openings N to any receptacle. By the provision of an apparatus embodying the features of my invention it will 85 be observed that cotton may be readily conveyed directly from the plant to a wagon or other receptacle upon which the suction-fan is carried.

Having thus described my invention, what 90 I claim as new, and desire to secure by Letters Patent, is—

A pneumatic conveying apparatus comprising a casing, a shaft journaled therein, fans rotating with said shaft, a screen fastened at its ends to the inner face of the cylindrical shell of the casing at points diametrically opposite, pipes leading from said casing, the ends of said pipes flaring and provided with eyes through which straps are adapted to pass

to hold the flaring ends of said pipes adjacent to the hands of an operator, as set forth. 10

In testimony whereof I hereunto affix my signature in presence of two witnesses.

WILLIAM BENNIE.

Witnesses:

T. C. WILKINSON,
S. W. JOHNSON.
